UNITED STATES PATENT OFFICE.

GEORGE DE VRIES, OF CHICAGO, ILLINOIS, ASSIGNOR TO AMERICAN LACE PAPER COMPANY, OF MILWAUKEE, WISCONSIN, A CORPORATION OF WISCONSIN.

FEEDING MECHANISM FOR BONBON-CUP MACHINES.

Application filed March 14, 1921. Serial No. 452,283.

To whom it may concern:

Be it known that I, GEORGE DE VRIES, a citizen of the United States, residing at Chicago, county of Cook, and State of Illinois, 5 have invented new and useful Improvements in Feeding Mechanisms for Bonbon-Cup Machines, of which the following is a specification.

This invention relates to improvements in 10 feeding mechanism for delivering sets of superposed paper blanks to the dies of machines used in the manufacture of paper bon bon cups, souffle cups and the like.

The object of this invention is to provide 15 improved means for removing the blanks from the stack in the magazine and for delivering each set or charge of blanks to the dies in an accurately superposed relation to each other and with all the blanks 20 in the set or charge properly centered with reference to the die.

More specifically it is the object of this 25 machine to provide blank or disk handling devices which will operate automatically without requiring the constant care of an operator, which will be positive in their 30 operation, and which will perform the feeding operation so accurately that waste will be reduced to a minimum.

30 In the drawings:

Figure 1 is a plan view of a bon bon cup machine embodying my invention, the magazine being removed.

Figure 2 is a side elevation of the same 35 with the magazine in place.

Figure 3 is a front elevation, with the magazine removed.

Figure 4 is a plan view of the delivery portion of the feeding mechanism.

40 Figure 5 is a front elevation on an enlarged scale, of the same mechanism.

Figure 6 is a sectional view likewise on an enlarged scale, taken on a plane indicated at 6-6 in Figures 4 and 5.

45 Like parts are identified by the same reference characters thruout the several views.

While the press, including the plunger, the die, and the means for operating the plunger, is of a common type, a brief description thereof is desirable to clearly set 50 forth the relation of the invention thereto.

The press and associated parts are mounted upon a table 1. A motor 3 at the rear of the table drives the main shaft 5 55 thru reduction gearing. The plunger 11 of

the press is given reciprocatory motion thru crank 6, connecting rod 7, and beam 8, these parts being supported by the standard 9. The plunger 11 carries a cross bar 12 in which the rods 13 have a sliding bearing. 60 A crimping member or annulus 15 and weights 16 are carried by rods 13 which have heads 17 limiting their movement relative to the cross bar 12. When the plunger is in a raised position it supports annulus 15 65 and weights 16 but as the plunger moves downwardly the annulus comes to rest upon the matrix 20 and the rods 13 slide in cross bar 12 allowing the plunger a continued movement. 70

The matrix 20 is heated by a gas burner 21. From its lower end a discharge chute 23 for the completed cups leads to the rear of the machine. The upper end of the matrix 20 is provided with teeth 24 with 75 which the teeth 25 upon the crimping member 15 are adapted to mesh. The inner surface of the matrix is provided with vertically disposed teeth, of which the teeth 24 on the upper surface constitute radial extensions in a manner well known in the art. 80

It will be understood that enough blanks are contained in the magazine 26 to supply the machine for some hours and that the blanks are removed from the magazine in 85 sets or charges, the number of blanks to the charge being determined by the position of the separating knife hereinafter described. These sets or charges of blanks are then delivered to the press in registry with the 90 serrated face 24 of the matrix 20 where they are clamped by the teeth 25 of the crimping member 15 and are there held by the pressure of weights 16 while their central portions are pressed downwardly by the forming head of the plunger 11, drawing the sides of the blanks between the teeth 24 and 95 25, which crimp them into a cup shape. During the forming process and after being so formed, the cups are subjected to heat developed by the gas burner 21 to permanently fix the shape, and they are finally forced by the accumulation of cups above them into the chute 23 which directs them to the rear of the machine. 100

The invention herein claimed being embodied in the feeder and its associated delivery mechanism for depositing the charge in exact registry with the die, these parts will now be more particularly described. 110

The mechanism which selects or separates a predetermined number of blanks from the stack in the magazine is termed the feed mechanism, the operation of which will now 5 be described.

A bearing plate 30 is bolted at 31 to the bed of the machine and is provided with slide grooves upon which the superimposed plates 32 and 33 are adapted to have independent movement transversely of the machine. The plates 32 and 33 are actuated by levers 34 and 35 controlled by a single cylindrical cam 36 having a cam groove 37 within which the pins 38 and 39 10 are mounted respectively upon the levers 34 and 35 are engaged upon diametrically opposite sides of the cam cylinder. Levers 34 and 35 are pivotally supported by bracket 40 and braced at 41 from the bed of the machine. The plates 32 and 33 carry blades 44 and 45. The under surface of the blade 44 is cut away forming shoulder 46, against which abuts the free end of the stripping member 47, pivoted at 48 to the under side of the blade. When stripping member 47 is in a raised position its under surface will be flush with the under side of shoulder 46. The blade 45 moves in close relation to blade 44 and its upper 20 surface is tapered toward its forward end so that the top of the blade 45 acts as a cam adapted to raise the stripping member 47 to a closed position relative to blade 44.

The disposition of the cam groove and the levers 34 and 35 is such that the blades 44 and 45 are alternately retracted from their advanced position in which blade 44 appears in Figure 3 to the position in which blade 45 appears in the same figure. The magazine 26 is provided with an opening in its side thru which the feeding blades can operate. Blade 44, in the position shown in Figure 3, will support the blanks in the mechanism, while the predetermined quantity about to be fed to the press is dropped onto the delivery mechanism (hereinafter to be described) by the withdrawal of blade 45. As the cam cylinder 36 rotates, the blade 45 will be projected forward and will 40 raise the stripper plate 47. In its most advanced position the blade 45 will be immediately below the position of blade 44 in Figure 3. The blade 44 will then begin its backward movement and will be entirely retracted from the magazine allowing the paper blanks to drop onto and to be supported by the upper surface of blade 45. Blade 44 will now return to the position shown in Figure 3, its sharp forward edge 45 entering the stack of blanks and separating a substantially definite number of them from the remainder of the pile. The number of blanks of any given thickness, which are thus separated is determined with sufficient exactness by the distance between the

blades 44 and 45. During the entering movement of this blade the stripper plate 4 will slide upon the raised portion of blade 45 so that its free end will move with blade 44 into the stack of blanks and will be engaged above the blanks which are to be fed. As soon as blade 44 reaches its advanced position, blade 45 will begin to retreat to the position of Figure 3 and will finally be withdrawn completely from beneath the 75 blanks which have been separated from those remaining in the magazine by the interposition of blade 44 which now carries the weight of the stack. The stripper plate will then have its free end resting upon the top 80 of the blanks and, being unsupported by the cam surface of blade 45, will fall, urged downwardly by its own weight, thereby forcing the blanks downwardly, should any of them tend to adhere to blade 44. It will 85 thus be evident that this feeding mechanism is capable of accurately removing a charge of given thickness from among the blanks in magazine 26 and depositing the charge so removed upon the delivery mechanism which 90 conveys the charge to the press. By providing interchangeable blades 44 and 45 having shanks of different thicknesses it is possible to determine the size or height of the charge. The number of blanks contained in each 95 charge will vary in accordance with the thickness of the paper but the total thickness will be a constant determined by the distance between the entering edges of the blades 44 and 45. This distance can be altered by providing blades having thickened inner ends or by placing shims beneath one of the blades. It is also within the scope of my invention to make these blades adjustable by providing set screws by which the 100 upper blade 44 may be raised above its normal position relative to sliding plate 33 in an easily understood manner.

The delivery mechanism, which is adapted to receive the charge of blanks from the 110 feeding mechanism and deliver it to the press will now be described.

A base block 50 is longitudinally slotted at 51 thruout the greater part of its length. It is provided with two sets of grooves, 115 shown in Figure 5 at 52 and 53, within which the slides 54 and 55 have a dove-tailed sliding bearing. Each of said slides is provided with a set of ears shown at 56 and 57 which project downwardly thru the slot 51 to a 120 point where they can be engaged by the operating levers 58 and 59 respectively, best shown in Figure 2.

The slide actuating levers 58 and 59 are keyed to shafts 60 and 61, which are rotatably journaled upon suitable supports carried by the table leg 2. To the rock shaft 60 is keyed the lever arm 62, to which is pivoted link 63, pivoted at its other end to the cam actuated lever 64. 130

A roller 65, carried by lever 64, is operatively associated with cam 66, carried by the main shaft 5. A second cam 67 of somewhat different form is also carried by shaft 5 and actuates the lever 68 thru the cam roller 69. Lever 68 is connected by link 70 and lever arm 71 with the rock shaft 61, which carries the slide actuating lever 59. Springs 72 and 73 actuate links 63 and 70 in the direction opposite to which they are urged by cams 66 and 67.

For the purposes of this specification, the lower of the two slides of the delivery mechanism, slide 54, will hereinafter be termed the carriage and slide 55 will be called, hereinafter, the positioning slide. The carriage 54 is provided with a longitudinal slot extending rearwardly from its front end throughout the greater portion of its length in which slot the ears 57 of positioning slot 55 have reciprocatory movement. Upon the forwardly extending arms, separated by the slot above referred to, are the integral blocks 74 to each of which is attached an elongated finger 75, preferably of resilient metal, upon which the paper blanks are deposited by the feeding mechanism, hereinbefore described.

The positioning slide 55 has a semicircular recess in its front end to which the arcuate plate 76 conforms. The plate 76 is fastened to the slide by means of screws 77 and is provided with notches 78 adapted to accommodate the resilient fingers 75. The semicircular recess, at the front of the positioning slide, and its arcuate lining plate 76 are so made that the inner surface of the plate 76 will conform exactly to the periphery of the paper blanks received upon the fingers 75.

For making bon bon cups of different sizes it is necessary to change the male and female die members, the crimping member, the magazine, and the positioning slide 55. All of these parts are made interchangeable. The die members are not only made in different sizes but are provided with different forms of teeth, whereby cups may be fluted in many different styles. The magazines are made in a number of diameters corresponding to the number of different blanks to be used. Likewise, interchangeable positioning slides 55 are provided, with recesses and plates 76 of various internal diameters corresponding to the sizes of blanks to be handled.

In Figures 5 and 6 of the drawings the carriage and positioning slide are represented as being built up of several pieces of different kinds of materials. In its preferred form the carriage will be made of brass, while the fingers 75 are made of a more resilient material. The brass carriage working upon the steel surfaces of the guide block 50 makes a good and serviceable bearing that will not stick. For like reasons the portion 55 of the positioning slide is of brass and the

re-enforcing portion 55^a of said slide may be of more rigid and cheaper metal such as iron or steel. This invention is not to be limited, however, to the use of any particular materials for the construction of the mechanism herein described.

In operation, the blade 45 of the feeding mechanism previously described is withdrawn to the position in which it appears in Figure 3, permitting a charge of blanks to drop upon the resilient fingers 75. The rotation of cam 67 allows the cam wheel 69 to reach the flat surface of the cam; and the pressure of spring 73, acting thru link 70, lever arm 71, rock shaft 61, and slide actuating arm 59, causes the positioning slide 55 to move inwardly toward the die, striking the charge of blanks which lies in the path of plate 76, upon the fingers 75. The cam 67 is so formed that positioning slide 55 attains its full speed quickly and strikes the charge of blanks with comparatively great impact. The blow tends to true up the stack and leave it with each blank in perfect registry with the others in the charge. In the rotation of cam 66, wheel 65 upon lever 64, now reaches the sharply dipping portion of said cam, and spring 72, acting thru link 63, lever arm 62, and slide actuating lever 58 causes the carriage 54 to move forwardly more rapidly than the positioning slide 55 so that the blanks resting upon the fingers 75 are carried out of contact with plate 76. The motion of the carriage 54 is sufficiently prolonged to carry the blanks supported by fingers 75 slightly beyond a position of perfect registry over the serrated upper face 24 of the matrix 20. At this time, the die plunger 11 carrying the crimping member 15 is already moving downwardly. The carriage 54 starts its return movement shortly before the positioning slide 55 reaches its most forward position. The positioning slide 55 stops with the inner surface of the plate or positioning stop 76 in registry with the periphery of the serrated edge 25 of the crimping member 15, and the paper blanks are then carried by the retracting fingers 75 into edge contact with the concave face of the then stationary plate 76 which arrests the retractive movement of the blanks, at the moment when they are accurately centered above the matrix and allows the fingers to withdraw from beneath them without displacing the blanks. The plate 76 remains in this holding position while the fingers of carriage 54 are being withdrawn and until the downwardly moving crimping member 15 engages the upper blank with its teeth 25. At this time the fingers 75 will just be withdrawn from beneath the blanks, which will now be engaged between teeth 24 of the matrix and the correspondingly serrated surface 25 of the crimping member 15. The weights 16 carried by arms 14 of said crimp-

130

ing member provide a constant and adjustable pressure upon the blanks. The plunger 11 continues its downward movement exerting a pressure upon the central portion of the charge of blanks drawing them between teeth 24 and 25 and crimping their edges upward into a cup-shape which is made permanent by the heat of burner 21. As soon as the clamping of the paper blanks between teeth 24 and 25 becomes effective the positioning slide 55, actuated by cam 67, starts its return movement toward the position in which it is shown in the drawings, wherein it is illustrated as about to receive a fresh charge of blanks from the feeding mechanism.

The above described operation is repeated indefinitely. It is only necessary for the operator to keep a supply of paper blanks in the magazine 26. As each fresh charge is forced by the die plunger 11 into the matrix 20, it causes the cups, previously made, to move one step downward until finally the matrix 20 is constantly full of cups and each stroke of the plunger 11 then forces one charge of the completed bon bon cups out of the bottom of the matrix into the chute 23.

It will be apparent from the foregoing that the delivery mechanism of my invention is extremely accurate in its operation. The first impact of the positioning plate 76 against the charge of dies upon the carriage trues up the stack and leaves the blanks in a position of perfect registry with each other. The second time the blanks come into contact with the plate 76, said plate functions as a positioning stop. The positioning slide 55 is at rest, holding the plate 76 in charge registering position. The carriage is just beginning its retractive motion and is moving very slowly when the charge contacts with the positioning stop 76. The impact is therefore very slight and the positioning stop operates effectively to hold the charge in exact registry with the matrix. Rebound effects are impossible because of the low speed at which the charge is moving. Also the fact that the carriage is being retracted at the moment when the charge impinges upon the positioning stop insures accuracy, for even should the charge rebound slightly, it would be again moved up into the proper position.

I claim:

1. The combination with a forming press provided with a die, of means for placing a predetermined charge of blanks upon the carriage, means for actuating the carriage in the direction of the die and across the face thereof, a reciprocable positioning member associated with the carriage and arranged to act upon the blanks carried thereby, means for actuating said positioning member in the direction of the die to a position of registry

therewith, and means for subsequently retracting said carriage, whereby the blanks upon the carriage will be brought into contact with the positioning member and will be maintained thereby in a position of registry with the die, pending engagement of the charge by operating parts of the press. 70

2. In a bon bon cup machine, the combination with a die and a machine bed, of guides carried by the bed, a carrier having sliding bearing upon said guides, and a positioning member independently slidable upon the guides and adapted to cooperate with the carrier in delivering material into a position of registry with the die. 80

3. In a bon bon cup machine, the combination with a machine table, a die, and a magazine, of means for removing a predetermined charge from the magazine, a carriage adapted to receive the charge so removed, 85 and a cooperating positioning device having movement independently of the carriage.

4. In a bon bon cup machine, a table, die mechanism and a magazine, in combination with a carriage reciprocable to and from the die, means for releasing upon the carriage a charge from the magazine, and means for holding the charge in registry with the die during the retraction of the carriage. 95

5. In a bon bon cup machine, a table, die mechanism and a magazine, in combination with a carriage reciprocable on the table to and from the die, fingers mounted upon the carriage in charge receiving position, an independently reciprocable slide adapted to cooperate with the carriage, a positioning plate borne by said slide and associated with the fingers of the carriage in stripping position, means for releasing a charge of blanks from the magazine upon said fingers, and means for actuating said carriage and the plate carrying slide, whereby said plate is adapted to hold each charge in registry with the die during the retractive movement of 110 the carriage and its charge supporting fingers. 105

6. A bon bon cup machine comprising a table, a die mechanism, a magazine, feeding mechanism adapted to remove a charge from the magazine, and delivery mechanism including a pair of reciprocatory slides adapted to receive said charge and deliver it to a position of registry with the die. 115

7. The combination with a magazine and forming press mechanism, of feeding devices including a pair of alternately reciprocatory knives adapted to remove a charge of material from the magazine, a carriage adapted to receive the charge so removed and to convey the charge to the press mechanism, and a positioning stop whereby the charge is held properly positioned with reference to the press mechanism pending the withdrawal of the carriage. 125 130

8. Mechanism for handling a stack of superimposed blanks, characterized by the combination of a carrier, a cooperating positioning stop, means for supplying the blanks to the carrier, means for actuating the stop to strike the blanks so supplied, means for actuating the carrier to carry the stack out of contact with the stop, means for arresting the movement of the stop in a blank registering position, and means for retracting the carrier to carry the blanks against the stop, whereby the blank supporting portions of the carrier may be withdrawn.

9. Means for delivering paper blanks to a forming press, said means comprising the combination of a blank carrier, a following positioning stop, means for arresting the movement of the stop in a blank registering position, and means for subsequently retracting the carrier to carry the blanks against the stop and withdraw the supporting portions of the carrier from beneath them.

10. The combination with a forming press of means for supplying paper blanks thereto, comprising a magazine, vertically spaced feeding knives adapted to protrude thru the side of the magazine to a blank supporting position, means for actuating said knives whereby they are alternately withdrawn from the magazine, a carrier beneath the magazine adapted to receive the blanks fed by the knives, mechanism for actuating said carrier to deliver to the press each charge of blanks received thereon, and a positioning stop cooperating with the carrier and

adapted to stop in blank registering position behind the blanks, whereby the carrier may be withdrawn from beneath the blanks.

11. The combination with a forming press, of means for supplying paper blanks thereto, comprising a magazine, vertically spaced feeding knives adapted to protrude thru the side of the magazine to a blank supporting position, means for alternately withdrawing said knives from the magazine, whereby a charge of blanks equal in height to the distance between the knives may be periodically discharged from the magazine, a carrier provided with fingers adapted to receive the charge and convey it to the press, and a cooperating positioning stop adapted to interact with said fingers to strip the charge therefrom upon the retractive movement of the carrier.

12. The combination with a forming press, of means for supplying blanks thereto, said means including a reciprocable slide provided with a blank supporting element, means for delivering a charge of blanks upon said element, a positioning slide associated with said first mentioned slide and adapted to conform at its forward end with the contour of the blanks to be formed, and means for actuating each slide reciprocally at predetermined periods during the operation of the press, said positioning slide being adapted to strip from said supporting element the blanks carried thereby.

GEORGE DE VRIES.
